UNITED STATES PATENT OFFICE

JAMES EDWARD TRAINER, OF BARBERTON, OHIO, ASSIGNOR TO THE BABCOCK & WILCOX COMPANY, OF BAYONNE, NEW JERSEY, A CORPORATION OF NEW JERSEY

LINK FOR CHAIN GRATE STOKERS

Application filed November 14, 1922. Serial No. 600,796.

My invention more particularly relates to a link which may readily replace a link of a chain grate.

My invention will best be understood by reference to the accompanying drawings, in which I have illustrated the preferred form of my invention, and in which Figure 1 is a fragmentary plan view of a section of a chain-grate stoker illustrating links formed in accordance with my invention in position on the transverse rods; Fig. 2 is a side view of a link formed in the chain; Fig. 3 is a plan view; Fig. 4 is a bottom plan view; Fig. 5 is an end view taken from the left of Fig. 2; Fig. 6 is an end view taken from the right of Fig. 2; Fig. 7 is a longitudinal section of a portion of the link taken parallel to the side thereof; Fig. 8 is a section taken on the plane of the line 8—8 of Fig. 7 looking in the direction of the arrows; Fig. 9 is a side view of the locking pin, and Fig. 10 is a plan view thereof.

Like reference characters indicate like parts throughout the drawings.

Referring, now, to the drawings, 11 is the surface portion of the link and 12 the web thereof, which is made narrower than the surface portion. The link made in accordance with my invention is preferably formed with a slot 13, and preferably extending longitudinally of the link, and in which a chain rod 14 is adapted to be received, the slot being provided with an open mouth 13^a extending to the bottom of the link. The link is also preferably provided with a second slot 15, which also extends longitudinally of the link, and which has an open mouth 15^a at the end of the link, the ends of the slots 13 and 15, respectively, being spaced the same distance as the center lines of two adjacent chain rods. The link is preferably provided on each of its sides with raised portions 16, which extend around the ends of the slots and beneath the same for the purpose of strengthening the lower portion of the link, the raised portions preferably being slightly wider than the surface portion of the link, as best illustrated in Figs. 2, 5 and 6.

The link formed in accordance with my invention, which is provided with a flat top,

is preferably provided with an opening 17 extending from the working face of the link to the upper wall of the slot 13, the lower portion of the opening preferably being contracted, as at 17^a, as illustrated in Fig. 7. 55 The wall of the link beneath the slot 13 is preferably provided with a recess 18 registering with the contracted portion 17^a of the opening. A pin 19 is adapted to be received in the opening 17, the lower portion of the pin being contracted, as at 19^a, to fit the contracted portion 17^a of the opening, and the lower end of the pin being received in the recess 18. The opening is so placed that the pin, when the link is in position on the chain rods, will come behind the rod, as illustrated in Fig. 7. The top of the pin 19, which is preferably formed of metal, is split, as at 20, the split portion coming opposite a transverse opening 21 in the chain link. Obviously the mouth of the slot in which the chain rod 14 is received, as illustrated in Fig. 7, may be completely closed by the cross pin 19, or may be only partially closed, as either arrangement would prevent the link from 70 slipping off from the chain rods. 75

In accordance with my invention, a broken link may be replaced while the chain is in movement by cutting out the broken link with a suitable tool, and then when the chain 80 is broken open at its end, the link formed in accordance with my invention may be dropped in position, the two slots engaging two adjacent chain rods, the link, of course, being inserted so that the direction of movement of the chain rod is toward the end walls of the slots. The pin 19 is then inserted in the opening 17, the end of the pin engaging the recess 18, and the outer end of the pin is spread by means of a suitable tool into the 85 opening 21, so that the pin locks the link in position on the chain rods. 90

A common cause of breakage of links is that in some cases one of the common links is compelled to pull other links. It is well 95 known to those skilled in the art that the ordinary chain grate stoker comprises transversely extending spaced chain rods which are connected by driving links for the chain, the chain grate also being provided with what 100

are called common links, that is, the other links that make up the chain grate and are located between the driving links. When the chain grate is functioning properly, the chain rods, of course, are driven by the driving links and the chain rods drag along the common links, each common link being called upon to pull only its own weight. In the case, however, of a link having a distance between the openings in the link which is less than standard, then that link necessarily pulls together the two adjacent chain rods which are engaged thereby and when this occurs, then that chain link is called upon not only to drag along its own weight, but the weight of certain adjacent links transversely of the chain. For example, if, when the chain is made up, one of the links has a center-to-center distance which is less than standard, then that link pulls together the two chain rods engaged thereby, and thereby causing the under-standard link to drag both its own weight and the weight of certain adjacent links as above indicated. This is likely to result in the breakage of the link. Again, as is well understood, the openings in the links in which the chain rods are received become enlarged because of wear, thereby spacing somewhat more widely the chain rods, and the usual chain grate has means for compensating for such wear. Now, if in such a worn chain a new link is inserted with a center-to-center distance the same as the links originally in the chain, then the new link will likewise pull together the engaged chain rods, thereby putting extra strain upon that link because it is compelled to drag along adjacent links and this again is very likely to result in breakage of that link.

Links formed in accordance with my invention and in the manner clearly illustrated in the drawings, overcome the foregoing difficulties. By forming the link with an open-mouthed slot (15) having a horizontally extending portion and which engages the chain rod on its upper and lower sides, the foregoing difficulties are avoided because that end of the link is free to move longitudinally over the chain rod engaged thereby.

At the same time, by forming the link with an open-mouthed slot having a portion extending longitudinally thereof, the longitudinal portion of the slot being greater than one-half the width thereof, in other words, greater than one-half the diameter of the chain rod, it will be apparent that the end of the link having the open-mouthed slot, merely rests upon its chain rod when passing along the upper or lower run of the chain, and when a closing member such as the pin is used for the open-mouthed slot, the pin is merely called upon to prevent excessive longitudinal movement of the link to prevent its falling from the chain.

What I claim and desire to secure by Letters Patent of the United States is:

1. In a chain grate stoker, a link having a transverse open-mouthed slot extending longitudinally of the link and adapted to receive a stoker chain rod, said link having an opening extending from the fuel supporting edge of the link to said slot, and a metallic pin in said opening and extending across the slot for locking the link in position on the chain rod, said link having a transverse opening opposite the end of said pin, and the top of the pin extending laterally into said transverse opening to hold the pin in position. 70

2. A link for a chain grate having chain rods, said link being provided with two open-mouthed slots each adapted to receive a chain rod and a portion of each being enclosed above and below, when the link is positioned in the upper run of the chain, by walls extending substantially parallel to the top face of the link, the upper and lower walls of said slots supporting said link on the chain rods, said slots being open at the same ends as regards the direction of movement, and means carried by said link and extending across the mouth of one of said slots to lock the link in position on the associated chain rods. 85

3. A link for a chain grate having chain rods, said link being provided with two open-mouthed slots each adapted to receive a chain rod and a portion of each being enclosed above and below, when the link is positioned in the upper run of the chain, by walls extending substantially parallel to the top face of the link, the upper and lower walls of said slots supporting said link on the chain rods, said slots being open at the same ends as regards the direction of movement, said link being provided with registering openings in the walls above and below one of said slots, and a pin adapted to be received in said openings, said openings being so positioned that the associated chain rod is locked in position in its slot between said pin and the end wall of the associated slot. 100

4. A link for a chain grate stoker provided with a first and a second open-mouthed slot each of which extends substantially parallel to the top of said link when the link is located in position in the top run of the chain and each adapted to receive a chain rod, the walls surrounding the slots being constructed and arranged to support the associated end of the link on said rod, and a pin extending into said second slot in front of the chain rod for retaining the link in position on said rod. 110

5. In a link for a chain grate stoker provided with a first and a second open-mouthed slot each of which extends substantially parallel to the top of said link when the link is located in position in the top run of the chain and each adapted to receive a chain 125

rod, the walls surrounding the slots being constructed and arranged to support the associated end of the link on said rod, said link being provided with an opening extending 5 from the surface of said top of said link to a position in said second slot in front of the associated chain rod, and a pin located in said opening and extending into said second slot in front of the associated chain rod, and 10 means for securing said pin in position in its opening.

6. In an endless chain grate, links each having two open ended slots therein receiving the cross rods of the grate, one of said 15 slots being arranged at an angle to the perpendicular to the longitudinal axis of the link, each link having an opening extending from a point accessible from the exterior at a turn of the grate to a point in the other slot 20 between its open end and the cross rod therein, and a pin in said opening extending into the last mentioned slot.

7. In an endless chain grate, links each having two open ended slots therein receiving the cross rods of the grate, one of said 25 slots being arranged at an angle to the perpendicular to the longitudinal axis of the link, each link having an opening extending from a point accessible from the exterior at a turn of the grate to a point in the other slot 30 between its open end and the cross rod therein, a pin in said opening extending into the last mentioned slot, and means for securing said pin in position.
